UNITED STATES PATENT OFFICE.

FREDERICK F. INGRAM, OF DETROIT, MICHIGAN, ASSIGNOR TO FREDERICK F. INGRAM COMPANY, OF DETROIT, MICHIGAN, A CORPORATION OF MICHIGAN.

PACKET.

1,170,159.

Specification of Letters Patent.

Patented Feb. 1, 1916.

Application filed June 12, 1915. Serial No. 33,813.

To all whom it may concern:

Be it known that I, FREDERICK F. INGRAM, a citizen of the United States of America, residing at Detroit, in the county of Wayne 5 and State of Michigan, have invented certain new and useful Improvements in Packets, of which the following is a specification, reference being had therein to the accompanying drawing.

10 The invention relates to packets, and resides in the provision of a novel construction packet that is adapted as a container for a small quantity of material, as for instance face powder or the like; and in the 15 provision of a simple and efficient packet which will form a suitable advertising medium for face powder or other toilet material, and yet may be cheaply manufactured.

20 The invention further resides in the novel construction, arrangement and combination of parts as hereinafter set forth and particularly pointed out in the claims.

In the drawings, Figure 1 is a perspective 25 view of a packet embodying the invention, the packet being shown in open position; Fig. 2 is a similar view with the packet in closed position; Fig. 3 illustrates the packet in partially folded position; and Figs. 4, 5 30 and 6 illustrate the manner of forming the packet.

The package is preferably formed from a blank A adapted to be folded along the line B to form sides C and D which in the 35 folded position of the packet are parallel. Secured to the inner face of one of the sides as C is a second layer of material such as the card-board member E. This member is preferably of the same size as the side C and 40 is provided with an open center or cut-away portion F forming a shallow chamber G, the chamber being closed at the bottom by the side C. In the preferred form of the invention there is secured to the side D a member H which is of a size to nicely fit the 45 chamber G. The portion cut out of the member E to form the chamber G may be utilized for the member H.

By the arrangement so far described, it 50 will be readily apparent that when the side D is folded upon the side C the member H will close the chamber G and will substantially fill this chamber. If powder or like material is placed within the chamber G the 55 member H will serve as a closure to retain

the powder in the chamber. The amount of powder the chamber G contains and the depth of the chamber may be varied as desired.

While the sides C and D may be secured together in various ways, in the preferred form of the invention the blank A is provided with flaps which are so constructed as to not only close the open end of the packet 60 opposite the fold B, but also to close the 65 sides of the packet. Thus as shown, I and J are flaps formed integral with the portion of the blank comprising the side D and foldable along the lines K and L respectively. Secured to the end of the side C is a flap M 70 having a lateral extension N. In the closed position of the packet the flap M is folded upon the outer face of the side D and the lateral extension N overlaps the flap J, the extension N being of a contour somewhat 75 similar to the flap J. The flap I is then folded over the outer face of the side C and the flaps J and N folded upon the flap I and the ends of these flaps inserted within a slot 80 O in the flap I, though other means of securing the flaps N and J and I in the closed position may be employed. When the flaps are so folded the open end of the packet opposite the fold B will be closed by the flap M, which is of a width equal to the width of 85 the side C adjacent the line P about which it is folded. Similarly the flaps I and J are of a width equal to the length of the side D at the lines about which they are folded and, therefore, close the side edges of the packet. 90 The closing of the various edges of the packet is desirable, since not only it prevents any material from discharging out of the packet, but also it forms a very tight closure for the material contained therein, which of 95 course is desirable for toilet powder or like material.

From the foregoing description it will be apparent that a very thin packet is provided which may be easily and cheaply 100 manufactured and which forms a suitable advertising medium or a suitable individual packet for guest rooms, hotels or the like.

What I claim as my invention is:

1. A packet comprising two sides folded 105 into parallelism, a chamber on one of the sides, and a projection on the inner face of the other side for closing the chamber.
2. A packet comprising a blank foldable upon itself to form sides, a member secured 110

to the inner face of one of the sides and having a cut-away portion forming a chamber, and a projection secured to the inner face of the other side and adapted to fit within said 5 chamber.

3. A packet comprising a blank foldable upon itself to form sides, a member secured to the inner face of one of the sides and having a cut-away portion forming a chamber, 10 a projection secured to the inner face of the other side and adapted to fit within said chamber, said blank having a flap attached to one of the sides and overlapping the other side.

15 4. A packet comprising a blank foldable upon itself to form sides, a member secured to the inner face of one of the sides and having a cut-away portion forming a chamber, a projection secured to the inner face of the 20 other side and adapted to fit within said chamber, said blank having flaps for closing all the open side edges of the packet.

5. A packet comprising a blank foldable upon itself to form sides, a member secured 25 to the inner face of one of the sides and having a cut-away portion forming a chamber, said blank having a flap at the end of one of the sides, and flaps on the opposite side edges of one of said sides, said flaps

serving to close the sides and the end of the 30 packet.

6. A packet comprising a blank foldable upon itself to form sides, a member secured to the inner face of one of the sides and having a cut-away portion forming a chamber, 35 said blank having flaps at the opposite side edges of one of the sides and having a flap at the end of the other side, the last-mentioned flap being provided with a lateral extension for folding over the flaps on the side 40 edges in the closed position of the packet, said flaps having an interlocking engagement.

7. A packet comprising a blank foldable upon itself to form sides, said blank having a flap at one of the side edges of one of the sides, formed with a slit and having a flap at the end of the other side, the last-mentioned flap being provided with a lateral extension for insertion in said slit when 45 the blank is folded.

In testimony whereof I affix my signature in presence of two witnesses.

FREDERICK F. INGRAM.
